Levitt & Tolpitsky
ATTORNEY

UNITED STATES PATENT OFFICE.

HERBERT ABRAHAM, OF NEW YORK, N. Y., ASSIGNOR TO THE RUBEROID COMPANY,
A CORPORATION OF NEW JERSEY.

INTERLOCKING SHINGLES.

Application filed June 13, 1922. Serial No. 568,001.

To all whom it may concern:

Be it known that I, HERBERT ABRAHAM, a citizen of the United States, residing in the city, county, and State of New York, ⁵ have invented certain new and useful Improvements in Interlocking Shingles, of which the following is a specification.

This invention relates to prepared roofing shingles and particularly to an improvement ¹⁰ in elements of the character described in my copending application Serial No. 489,971, filed April 11, 1922.

The object of the invention is to provide improvements in such shingles by which the ¹⁵ roof may be covered with less material and will present an attractive appearance, and in which the lower ends or butts of the shingles will be securely held down.

In the accompanying drawing:

²⁰ Fig. 1 is a plan view of a plurality of courses of overlapped shingles as laid on a roof, the covered portions of the several shingles being indicated by dotted lines, and

²⁵ Fig. 2 is a plan view of several shingles laid side by side in a row.

While I have illustrated the improvement with reference to individual shingles it is to be understood that it may be embodied in strips consisting of a plurality of shingles integrally connected together.

The improved shingle is made of prepared roofing comprising a foundation of felt or fibrous material, saturated and coated with bituminous compositions, and generally faced ³⁵ on its weather surface with crushed slate or other mineral particles.

Each shingle comprises a body 1 having a straight edge 2 and having an extension centrally disposed on the opposite edge to provide a shoulder 3 at either side of the base of the extension. The extension comprises two mutually similar portions 4 and 5 of trapezoidal form, disposed one above the other with the narrow end of the upper portion joining the wide end of the lower portion. The width of the extension at its middle and outer end is similar and equal to double the width of a shoulder 3 so that when several shingles are laid side by side ⁴⁵ in a row, as seen in Fig. 2, uniform spaces will intervene adjacent extensions.

A vertical slit 6 is formed at either side of the base of the extension, said slits extending inwardly of the body to a depth

⁵⁵ equal to the vertical dimension of the lower portion 5 of the extension which dimension, in the preferred form of shingle, is equal to half the length of the entire extension.

In laying the roof, the shingles are placed in overlapping courses with the laterally ⁶⁰ projecting corners of the portions 5 of the extensions of each course engaged in the slits 6 of the immediately underlying course in the manner shown in Fig. 1, thereby interlocking the several courses and holding ⁶⁵ down the butts of the shingles.

What I claim is:

1. A prepared roofing shingle comprising a body having an extension on one edge intermediate the ends, the sides of the extension each having a re-entering angle in opposite parts, the width of the outer end of the extension being substantially equal to the width between the innermost points of the angles, the body having an inwardly extending slit at either side of the base of the extension, the lengths of the slits being substantially equal to the distance from the outer end of the extension to the innermost points of the angles measured vertically. ⁷⁰

2. A prepared roofing shingle comprising a body having an extension on one edge intermediate the ends, the sides of the extension each having a re-entering angle in opposite parts, the width of the outer end of the extension being substantially equal to the width between the innermost points of the angles, the body having an inwardly extending slit at either side of the base of the extension, the length of each slit being ⁷⁵ substantially one-half the length of the extension. ⁸⁰

3. A prepared roofing shingle comprising a body having an extension on one edge and having a shoulder at either side of the extension, the sides of the extension each having a re-entering angle in opposite parts, the width between the innermost points of the opposite angles being substantially twice the width of a shoulder, the body having an inwardly extending slit at either side of the base of the extension, the lengths of the slits being substantially equal to the distance from the outer end of the extension to the innermost points of the angles measured vertically. ⁸⁵ ⁹⁰ ⁹⁵ ¹⁰⁰

HERBERT ABRAHAM.
